UNITED STATES PATENT OFFICE.

WIRT W. WALTON, OF NEW YORK, N. Y., ASSIGNOR TO NOMA MOTOR CORPORATION, OF NEW YORK, N. Y., A CORPORATION OF NEW YORK.

DESIGN FOR AN AUTOMOBILE-WINDSHIELD.

55,444.

Specification for Design.

Patented June 8, 1920.

Application filed March 12, 1920. Serial No. 365,329. Term of patent 7 years.

To all whom it may concern:

Be it known that I, WIRT W. WALTON, a citizen of the United States, residing in Manhattan, in the city, county, and State of New York, have invented a new, original, and ornamental Design for Automobile-Windshields, of which the following is a specification, reference being had to the accompanying drawing, forming part thereof.

Figure 1 is a rear face view,
Fig. 2 is an end view, and
Fig. 3 is a top plan view.

I claim:

The ornamental design for an automobile windshield, as shown.

WIRT WARD WALTON.
